UNITED STATES PATENT OFFICE.

CHARLES O. PEARSON, OF NEW YORK, N. Y.

HOISTING APPARATUS.

1,026,118.

Specification of Letters Patent.

Patented May 14, 1912.

Application filed February 6, 1908. Serial No. 414,475.

To all whom it may concern:

Be it known that I, CHARLES O. PEARSON, a citizen of the United States, and a resident of the borough of Brooklyn, in the county 5 of Kings, city and State of New York, United States of America, have invented certain new and useful Improvements in Hoisting Apparatus, of which the following is a specification.

10 My invention relates to improvements in hoisting apparatus and more especially to elevators of the type which is commonly known as traction elevators in which the movement of a driven sheave is imparted 15 to a car through the medium of a rope or cable in frictional contact with the sheave.

The object of my invention is to provide a simple and efficient apparatus of this kind and it consists in the construction and arrangement of parts which are shown and described in the following specification and the novel features whereof are pointed out in claims.

Referring to the drawings, Figure 1 is a 25 side elevation of a hoisting apparatus and its associated parts made according to my invention. Fig. 2 is a diagrammatic representation of a driving rope or cable illustrating the manner in which it is passed around the driving sheaves, the position of the sheaves in this figure being inverted from that in which they are shown in Fig. 1. Fig. 3 is a sectional side elevation of a rope-drive apparatus which I have invented. 30 Fig. 4 is a top plan view of my improved apparatus. Fig. 5 is a front elevation of the apparatus shown in Figs. 3 and 4 with certain parts broken away to more clearly show its construction. Fig. 6 is a sectional 35 end elevation of the apparatus, the view being taken from the rear and the section being taken on the line 6—6 of Fig. 4. Fig. 7 is another sectional rear end elevation of the apparatus, the section in this case being 40 taken on the line 7—7 of Fig. 4.

Like characters of reference designate corresponding parts in all of the figures.

10 designates a driving sheave which is keyed or otherwise attached to a shaft 11 50 which is supported in stationary bearings 12, 13 and 14. 15 is a gear-wheel attached to the shaft 11 between the bearings 12 and 13. 16 is a small gear or pinion which may be made of metal or raw-hide or other suitable material. This is attached to a shaft 17 which is an extension of or is directly

coupled with the shaft of a motor 18. 20 is another driving sheave attached to a shaft 21 which is mounted in bearings 22 and 23. 25 is a gear-wheel between the bearings 22 and 23 and also attached to this shaft. A small gear or pinion 26 is in mesh with the gear 25. This pinion is attached to a shaft 27 which is an extension of or is directly coupled with the shaft of a motor 28. 60 65

30 is the lower portion of a casing which forms a base or foundation for the hoisting apparatus which supports or forms a part of the bearings 12, 13 and 14, forms a bed-plate for the motors 18 and 28 and performs the other functions which will be pointed out hereinafter. 31 is the upper portion of this casing, and this part supports or is a part of the bearings 22 and 23 and is arranged to inclose certain parts of the mechanism. 32 is a cover for the gear 25 and may be arranged as shown to form parts of the bearings 22 and 23. These parts 30, 31 and 32 may be suitably fastened together as by bolts as shown. 70 75 80

The general arrangement of the apparatus, as shown in the drawings and above described, is symmetrical and compact. The two driving sheaves are one above the other in a vertical line and the two motors are 85 also in a line which is at right angles to that of the sheaves, while between the sheaves and the motors is a casing inclosing intermediate connecting mechanism. Of course this is not an essential part of my 90 invention but is a preferred arrangement of the parts as it requires but little space for its installation.

33 designates a rope or cable which is attached to an elevator car 34 and which, after passing over a supporting sheave 35 suitably supported upon the building or structure near the upper end of the path of travel of the car, is carried down to and under the driving sheave 10; thence it passes over the driving sheave 20 down under driving sheave 10 again and then up to and over another supporting sheave 36 from whence it extends downward to the counterweight 37 to which its other end is attached. 95 100 105

I have described the run of one rope or cable, but in practice a plurality of them is used as is shown in Fig. 3. It is also to be understood that instead of being passed once over sheave 20 and twice under sheave 10 the ropes may be given as many turns about these driving sheaves as may be de- 110

sired to increase the amount of frictional contact between the rope and the driving sheaves. The sheave 20 is shown as being of smaller diameter than that of sheave 10 as this is a preferred arrangement, but it may be of the same diameter or even of greater diameter than that of the sheave 10 if desired.

Before proceeding with the description of the details of construction which I have invented and have shown in the drawings, I will point out the operation of the apparatus above described. It may be seen that the motor 18, through gears 16 and 15, is arranged to actuate the driving sheave 10; similarly, the motor 28, through gears 26 and 25, actuates driving sheave 20. Thus there are two driving systems which are entirely independent of each other and which have no mechanical connection between them, except through the driven rope or cable 33. This mechanical connection, through the rope itself, will cause the two driving sheaves to rotate at the same rate of peripheral speed and to exert a uniform traction on the rope but one of great flexibility. This flexibility effectively does away with internal strains due to improper proportioning of the gears and sheaves, or due to the slipping of the ropes on the sheaves. It has been found in other devices of this kind in which both of the sheaves, such as 10 and 20, are geared together and are motor-driven, that there has been a great wear and tear on the ropes as well as on the machinery as there is always a certain amount of slippage between the rope and each driving sheave and the amount of such slippage on one sheave is different from that on the other. The consequence is that the ropes wear out rapidly and the efficiency of the apparatus is decreased.

Electric motors are shown as the motive power. While I do not limit myself to this means of driving the sheaves I prefer it as the electrical connections between the motors, which connections may be made in any desired manner, form another flexible connecting means between the two independent driving units which allows more or less relative variation between the speed of the two driving sheaves without putting any strains on the mechanism and without mechanical losses.

In the arrangement of parts shown the motors are accessible for repairs and may be directly coupled with the driving sheave shafts as is now done in some instances with a single motor and a single driving sheave, but as this requires a very large slow-speed expensive motor I prefer to use smaller motors with speed reduction mechanisms between the motors and the driving sheaves.

I prefer also to use spur gears for this purpose on account of their simplicity, effi-

ciency and other advantages which they possess. The casing which supports and encloses the gears is arranged to provide an oil bath for them as is shown at 19 and 29 in Fig. 3 of the drawings. By using this construction with motors of comparatively slow speed the apparatus will run practically noiselessly and thus be free from one of the objectionable features of such a mechanism for elevator purposes. Another objection to the use of spur gears in elevator driving mechanism is that a certain amount of vibration due to the action of the gear-teeth is transmitted to the car. This trouble is overcome by my improved construction on account of the fact that the two driving mechanisms do not run at exactly the same rate of speed so that the vibrations from the gear-teeth in the two units are non-synchronous and the flexible connection between the two effectively breaks them up. Another advantage of this method of driving elevators by two independent driving systems is that either motor may be used alone to drive the car in case of emergency, thus making repairs possible without necessitating the shutting down of the elevator. The apparatus is adaptable for high speed passenger service elevators or for slow speed freight elevators but is not, of course, limited to such uses as it may be applied to all kinds of rope-driven apparatus including telpherage systems and furnace hoists.

In conjunction with Fig. 1 I have shown a diagram of electrical connections for the motors. In this figure 40 designates the mains from a suitable source of electrical supply which, after passing through a main-line switch 41, are connected with the various contacts of an electrically actuated reversing switch 42, 43 and with a controlling switch 44 in the car 34. When this car switch is moved to the left the right-hand side 43 of the reversing switch will be closed, and when it is moved to the right, the left-hand side 42 of the reversing switch will be closed. This will send a current through the armatures 18^A and 28^A of the motors in one direction or the other, and as it will also connect the fields 18^B and 28^B with the line, it will cause the motors to rotate in one direction or the other. Bringing the car switch back to its central position will cause the reversing switch to be deenergized to break the circuits through the motors so as to cause them to again come to rest. In the drawing the armatures are shown connected in series and the fields connected in parallel. The particular arrangement of the circuits shown forms no part of this invention as any preferred wiring system may be employed, and as these are well known in the art, only a brief description of the one which I have arbitrarily selected to illustrate my invention is given above.

Electrical motors of comparatively slow speed are preferable for carrying out this invention, but if the motors are connected as shown in the drawings and above described, 5 high speed motors may be used and run at a reduced rate of speed on account of the peculiar arrangement of the circuits.

Referring more especially to Fig. 7 I will describe a brake which I have invented. 10 50 designates a brake-pulley suitably attached to the shaft 11. A pair of brake-shoes 51, 51 are connected with levers 52, 52 which are pivoted at 52^A, 52^A. The upper ends of these 15 brake-levers are connected together and to a vertically reciprocatory rod 53 by two short arms 54. These parts are inclosed in a casing 55 which is adapted to contain oil and to keep the surface of the brake-pulley 50 and the brake-shoes 51 thoroughly lubricated at 20 all times. A spring 56 is arranged to press the inner ends of the arms 54 downward and to thus press the brake-shoes against the surface of the brake-pulley with an amount of pressure which may be regulated by means 25 of a threaded collar 56^A. 57 designates the frame of an electromagnet or solenoid. 58 is its core or plunger and 59 its winding. The plunger is attached to the rod 53 and the parts are so arranged that when a current 30 of electricity is passed through the winding the core will be raised thereby and will release the brake by moving the shoes away from the pulley 50. Above the magnet frame 57 is a dash-pot 60 which comprises a cylinder 61 and a piston 62. At the 35 top of the cylinder is a ball check-valve 53 which allows free outward passage of air from the part of the cylinder above the piston, but prevents any inward flow of air, 40 which flow must take place through a restricted passage 64, the size of which is adjustable. The brake may be released quickly, but when current is cut off from winding 59 to allow the weight of the core 45 58 and the spring 55 to apply the brake-shoes, this operation will be controlled or timed by the dash-pot and may be regulated by the size of the restricted passage 64. In the wiring diagram in Fig. 1, one method 50 of connecting the winding 59 is illustrated. In brakes of this general construction it has been a matter of difficulty to obtain a uniform action of the brakes under different 55 conditions, because they are normally actuated with dry braking surfaces, and when any lubricant gets upon them accidentally they slip and fail to properly perform their function. According to my invention the 60 braking surfaces are always freely lubricated and the brake made powerful enough to act properly under this condition. The lubricant also serves to keep the parts cool so that their adjustment is not deranged by temperature changes.

65 I also prefer to use brakes on the motor

shafts 17 and 27 and these are clearly shown in Fig. 6. In this figure 70 is a brake-pulley; 71, 71 brake-shoes on pivoted levers 72, 72 which are connected together and to a vertically reciprocatory rod 73 by links 74 and levers 74^A. 75 is a casing inclosing the above parts and arranged to contain lubricating oil. The rod 73 is actuated by a spring 76 and the core 78 of a solenoid or magnet of which 77 is the frame and 79 the winding. 80 is a dash-pot which is arranged to control the action of these brakes. These parts operate in the manner above described, but in this case two brakes are actuated by the magnet. The winding 79 may be connected in the wiring system in parallel with the winding 59 or in any other suitable manner. By means of the dash-pots 60 and 80 the brakes may be so adjusted or timed that the brakes on shafts 17 and 27—which 85 are on the high-speed side of the reduction mechanisms—are applied before the brake on shaft 11, on the slow-speed side of one of these mechanisms goes on. This arrangement insures a smooth stopping of the 90 elevator. If desired, another brake may be applied to shaft 21 but this I believe to be unnecessary.

What I claim is:—

1. A pair of traction sheaves, a pair of 95 electric motors, separate intermediate mechanisms connecting each motor with one of the sheaves, the axes of the sheaves and the motors being parallel and the two motors being in a line at right-angles to the line between 100 the sheaves; and a rope or ropes in frictional contact with both of the sheaves forming the only mechanical connections between the sheaves.

2. A traction sheave, a motor, a spur 105 gear connected with the sheave, a pinion meshing therewith and connected with the motor; a second traction sheave, a second motor, a spur gear connected with the second traction sheave, a pinion meshing therewith and connected with the second motor, a casing inclosing the gears and pinions and supporting the traction sheaves and the 110 motors at right-angles to each other, and a rope or ropes in frictional contact with both 115 of the sheaves forming the only mechanical connection between the sheaves and the two motors.

3. A traction sheave, a motor, a spur gear connected with the sheave, a pinion meshing therewith and connected with the motor; a second traction sheave, a second motor, a spur gear connected with the second traction sheave, a pinion meshing therewith and connected with the second motor, a casing inclosing the gears and pinions, a lubricating bath within the casing, said casing supporting the traction sheaves on one side thereof and the motors on the other side thereof and at right-angles to the sheaves, 130

- and a rope or ropes in frictional contact with both of the sheaves forming the only mechanical connection between the sheaves and the two motors.
5. 4. In combination with an elevator hoisting apparatus comprising a pair of traction sheaves, means for driving each of said sheaves independently of the other, and a rope about the sheaves forming the only mechanical connection between the sheaves; a plurality of brakes, one of said brakes being arranged to be applied before the other or others.
10. 5. In combination with an elevator hoisting apparatus, comprising a pair of traction sheaves, a motor for driving one of the sheaves, another motor for driving the other of the sheaves, and a rope about the sheaves flexibly connecting them together; a brake for one of the traction sheaves, brakes for the motors, means for actuating all of the brakes, and means for causing the brake for the traction sheave to be applied after the motor brakes have been applied.
15. 6. In combination with an elevator hoisting apparatus comprising a pair of traction sheaves, a motor for driving one of the sheaves, another motor for driving the other of the sheaves, independent speed reduction mechanisms between the motors and the traction sheaves, and a rope about the sheaves flexibly connecting them together; a brake on the slow-moving end of one of the reduction mechanisms, a brake on the
20. 30. 35. fast-moving end of the other speed reduc-
- tion mechanism, means for actuating both of the brakes, and means for causing the brake on the fast-moving end of the speed reduction mechanism to be applied before the brake on the slow-moving end of the other speed reduction mechanism is applied.
7. In combination with an elevator hoisting apparatus comprising a pair of traction sheaves of different diameters, a motor for driving the larger of the sheaves, another motor for driving the smaller of the sheaves, independent speed reduction mechanisms between the motors and the traction sheaves, and a rope about the sheaves flexibly connecting them together; a brake on the slow end of the speed reduction mechanism which is connected with the larger sheave, a brake on the fast-end of the speed reduction mechanism which is connected with the smaller sheave, means for actuating both of the brakes, and means for causing the brake on the fast end of the speed reduction mechanism which is connected with the small sheave to be applied before the brake is applied to the slow end of the speed reduction mechanism which is connected with the large sheave.
40. 45. 50. 55. 60. 65. In testimony whereof I have signed my name to this specification in the presence of two subscribing witnesses.

CHARLES O. PEARSON.
